UNITED STATES PATENT OFFICE.

VERNON ROYLE, OF PATERSON, NEW JERSEY.

DESIGN FOR A ROUTER-SUPPORTING FRAME.

SPECIFICATION forming part of Design No. 33,972, dated January 22, 1901.

Application filed December 28, 1900. Serial No. 41,422. Term of patent 14 years.

To all whom it may concern:

Be it known that I, VERNON ROYLE, a citizen of the United States, and a resident of Paterson, in the county of Passaic and State 5 of New Jersey, have invented and produced a new and original Design for a Router-Supporting Frame, of which the following is a specification.

The essential features of my design consist 10 in a supporting-frame for routing-machines, presenting a pillar having an extended base, smaller pillars uprising from the base, and a superposed structure comprising a cap-piece at the top of the main pillar with arms slanting upwardly therefrom.

In the accompanying drawings, Figure 1 is 15 a view of the supporting-frame in front ele-

vation. Fig. 2 is a view of the same in side elevation, and Fig. 3 is a top plan view.

The main pillar is denoted by *a*, its base 20 by *b*, the smaller pillars uprising from the base by *c d*, the cap-piece by *e*, and the arms slanting upwardly from the cap-piece by *f g*.

What I claim is—

The design for a router-supporting frame, 25 substantially as herein shown and described.

In testimony that I claim the foregoing as my invention I have signed my name, in presence of two witnesses, this 20th day of December, A. D. 1900.

VERNON ROYLE.
